FUEL INJECTION SYSTEM

Robert E. Nelson, Pasadena, Calif.

Application July 22, 1936, Serial No. 91,949

3 Claims. (Cl. 123—139)

This invention relates to fuel injection in internal combustion engines. It operates on the well-known principle of the hydraulic ram, which may be stated as follows:

5 When a column of liquid confined by a duct is given a high velocity of flow along the duct and then abruptly brought to rest, pressure is generated, amounting for the more common liquids to about 60 pounds per square inch for each foot 10 per second of extinguished velocity.

In previous attempts known to me to apply this principle to the problem of fuel injection, fuel in a duct has been brought to the required velocity by means of pressure at the upstream 15 end of the duct supplied by a pump delivering from a suitable source. At the downstream end the fuel was permitted to return to its source until the flow was stopped, more or less abruptly, by the closing of an engine-operated valve.

20 In the present invention I prefer to employ for the same purpose a reciprocating engine-operated displacer. This displacer produces momentarily a substantial pressure at the upstream end of the ram duct by its displacement of fuel there, preferably into an adjacent accumulator, and simultaneously yields downstream a space to receive flow through the duct. When this space, which is limited in extent, becomes filled, the flow into it is automatically terminated and the rapidly 25 moving column of fuel brought to rest, except for a small amount of delivery at high pressure to the injection nozzle lasting the time required for one round trip of the flow-curtailing wave through the ram duct.

30 This method of terminating flow is clean and sharp, and permits of an exceptionally short length of ram duct, giving a correspondingly short injection wave. This is particularly advantageous in high-speed engines, especially in those employing high dispersion injection nozzles, since the nozzle opening may be made substantially greater than has heretofore been practicable. Not only does it become easier to obtain uniform dispersion of the spray but also the penetration 35 of the short, intense discharge resulting is greatly superior to that obtainable from smaller-opening relatively slow-discharging nozzles of similar design. I prefer to employ an outwardly-opening automatic poppet injection valve where the design of the engine will permit. I have found it feasible to tune such a valve to the period of the injection wave; so that the valve swings open and closed again just once during the incidence 40 of the wave.

55 Other features and advantages of my inven-

tion may best be made apparent from a study of the following description and of the drawings.

In the drawings, Figure I is a comprehensive view of a preferred embodiment of my invention, partly in section and partly in diagram. In Figure II the operation of the system is graphically analyzed to show the sequence of events.

In Fig. I the numeral 1 represents an engine cylinder and 2 its piston, which, in cooperation with the cylinder head 3, form the combustion 10 chamber 6 when the piston is near the top of its stroke, where it is shown. Conveniently built into the head 3 are the injection wave generator 4 and the injection valve 5. This valve is of the poppet type and forms, when open, an annular 15 orifice directed to reach most of the air in the combustion space. The injection wave generator 4 is operated hydraulically in response to the engine cycle by a wave of pressure coming along the line 9 from the operating unit 7, conveniently mounted on the engine 10 and itself operated by means of cams on the camshaft 80. The camshaft is engine-driven through the symbolically indicated drive 8, with which may be combined any one of the suitable well-known 20 mechanisms for advancing the timing of operation automatically at high speeds of the engine.

The injection orifice is formed at 55 by the lifting of the valve head 52 from its seat 51 under the pressure of the injection wave. The amount of 25 opening is determined by the elasticity of the slender valve stem 53, acting as a tension spring. The valve parts are centered at 54, where the stem is given an enlarged diameter for a short length to fit into a guide bore in the seat-piece 30 51. Passages 56 in 51 give the fuel injection pressure access to the valve. By means of the threaded enlargement 57 at the inner end of the valve stem and the nut 582, the valve is secured to the automatic take-up plug 581, which fits 35 into the bore 584 in the head 3. The plug 581 is closed by the cap 585, thus leaving a small space at 587. This space and the chamber 48, formed in the head 3, are kept filled 40 with fuel. The plug 581 should fit its bore 584 with slight looseness to permit adjustment flow past itself to allow the spring 586 to define the opening pressure of the injection valve, which 45 pressure should be great enough to prevent opening of the valve except at the time of the generation of the injection wave. High momentary pressure in 48 occurs at the time of injection, as will be seen, and opposes movement of the plug 581 under the increased stem stress when 50 the injection valve is open.

41 is the displacer of the injection wave generator 4. This displacer is stepped in diameter and fits at 411 and 412 with a correspondingly stepped bore in the sleeve 43, which is set into the head 3 snugly at 431 and 432, securing the valve piece 51 and secured by the retainer 44. This retainer and the seatpiece 51 limit the travel of the displacer at 46 and 47 respectively. The ram column 42 is formed axially in the displacer, and is conveniently passed through longitudinally by the valve stem 53.

The displacer is operated on its active stroke by hydraulic pressure on the face 45 between the ends of different diameters. This pressure comes along the line 9 from the operating unit 7. In turn the displacer forces fuel from the space at its end 46 into the fuel-filled chamber 48, and at the same time creates a space at its end 47 downstream of the ram column. Under the pressure built up in 48 by the upstream displacement, a flow develops in the ram column, and continues until the space at 47 created by the movement of the displacer becomes completely filled, at which time wave generation occurs.

The ram column 42, the passages 56 and the fuel compression chamber 48 are kept filled with fuel at a pressure which may be conveniently about 150 lbs. per sq. inch by means of a supply system as follows:

Fuel from any convenient source such as a tank 100 is taken by the line 101 to the pump 102, which may be an engine-driven gear-pump. This delivers into a stabilizing duct or reservoir 103. From this the tube 104, at least a part of which is of small section, goes to the chamber 48. From the chamber, preferably at its highest point, another tube 105 having a length at similar small section leads to the second reservoir 106, the pressure in which is maintained at the desired average value by the loaded relief valve 107, which discharges back through the line 108 to the source of fuel.

The pump 102 should be of sufficient capacity to deliver fuel in excess of that required for injection in order to maintain a net flow out of the chamber 48 through the tube 105, by which any air in 48 may be exhausted. At the time of compression in 48 by the action of the displacer 41 the pressure in 48 will be high. The small tubes 104 and 105, since they resist by the inertia of their columns changes in flow, permit this high pressure momentarily but serve to discharge quickly any residual pressure at the end of the period of activity of the wave generator. As will be seen later, a reflected wave returns from the injection valve. This causes some surging from the ram column into the chamber 48, which the tubes, especially 105, largely absorb.

The body of the operating unit, indicated by 7, is mounted conveniently on the engine to permit its camshaft 80 and its tappets 713 and 723 to be built into the engine. Into the body 7 is formed the chamber 70, which is filled with a suitable grade of lubricating oil. Threaded into the bottom of this chamber is the barrel 710, to which is fitted the plunger 711, operated by the cam 712 through the tappet 713 and returned by the spring 714. Between the chamber 70 and the line 9 is the bore 731, to which is fitted the plunger or "release-displacer" 73. This release-displacer is enlarged on its bottom face to seat against the end 720G of the barrel 720, which has its plunger assembly including the release plunger 721, the cam 722, the tappet 723, and the spring 724. A spring 732, held by the retainer 733, urges the release-displacer toward its seat. A

small hole 730 is drilled in the face of the release-displacer to permit a limited degree of communication between its ends.

In operation the plunger 711 builds up a high pressure in 70 until the plunger 721 is advanced. This plunger unseats by hydraulic pressure or direct contact the release-displacer 73, which is then driven forcefully into the bore 731 for a short distance, transferring by its displacement the energy of the compression chamber to the line 9. The throttle valve 71, which may be manually operated or governor-controlled, regulates the intensity of the outgoing wave as desired for control of the intensity of the injection wave and thus for control of the amount of fuel injected.

The line 9 and the chamber 70 are initially filled with lubricating oil. Any subsequent leakage of this liquid is made up by leakage of fuel past the displacer 41 under the pressure of the supply system. It will be seen that the displacer 41 will be returned to its initial position after active operation by the supply pressure when return is permitted by the operating unit 7. The plunger 711 recedes slightly earlier than the release-plunger 721. During this return, accompanied by return of the release-displacer, any deficiency in liquid in 70 will be made up by flow through the hole 730. The plunger 721 finally permits the release-displacer to seat, and recedes somewhat farther until the time for its next lifting.

In Fig. II the operating characteristics of the system are plotted for maximum usable engine speed and full injected charge. The curves are somewhat idealized and are intended to show only in a general way the actual conditions in the system to indicate the sequence of events. At the top of the chart the movements of several parts are plotted against time in degrees of crank angle to the same linear scale. The curves are numbered to correspond to the parts to which they refer. Pressure variations for a number of points in the system are similarly plotted below. These pressures, given in thousands of pounds per square inch are, of course, not the only ones for which the system may be designed.

The members of the system are in the position shown in Fig. I at about -70 degrees, or 70 degrees before top center, with the releasing plunger 721 still descending slowly. At about -66 degrees the cycle of operation of the system begins as the cam 712 starts to lift the plunger 711. As this advances the pressure in 70 rises proportionately. This compression continues until release at about -26 degrees.

The releasing plunger starts to rise at about -28 degrees but does not cause release until the volume swept on the previous return after closing and not containing liquid has been made up. Unseating will normally be by hydraulic pressure, but if, for any reason, this is not the case, the plunger 721 will unseat the release-displacer at about -24 degrees by direct contact.

As soon as unseating permits the pressure in 70 to govern, the release-displacer is rapidly accelerated, producing by its motion a strong wave to go out along the line 9. At the same time the pressure in 70 will fall off rapidly, and becomes negligible at about -17 degrees. The intensity of the outgoing wave reaches its maximum early and later falls off more slowly than does the pressure in the chamber, because of the momentum of the release-displacer.

At about -21 degrees, depending upon the length of the operating line 9, the operating wave

reaches the displacer 41, which immediately starts to move in response to the pressure. This pressure, high at the start, falls off rapidly; most of the energy given the displacer comes during the first part of its motion. In the meantime the pressure in the fuel compression chamber 48 builds up, so that, during the later part of the movement of the displacer this pressure is dominant and brings the displacer to rest, in cooperation with the retainer 44 against which the displacer subsequently bears. While the displacer goes through its movement, the fuel in the ram column accumulates velocity of flow into the space at 47, which it fills completely at the time that the displacer 41 ends its motion. It is then, at about -10 degrees, that the injection wave is generated, beginning at the downstream end of the column.

When the space at 47 has filled, the moving column of fuel in the ram column is forced to seek an outlet through the passages 56, which, however, being filled with stationary fuel, resist flow and force the development of a high pressure at 47. This pressure, sufficient to equalize the flow in ram-column and passages, travels in both directions in a wave with the velocity of sound. When this wave reaches the compression chamber 48 a wave of decompression to the pressure of the chamber 48 immediately begins to return along the column. The total time that the downstream end of the column is at high pressure is, then, that required for one round trip of a wave in the ram column. This is the period of the injection wave.

When the forward wave reaches the head 52 of the valve, it is, at first, almost totally reflected, since the valve is closed; so that the pressure almost doubles. The valve opens rapidly, and continues to open as the pressure is partially relieved by the discharge through the injection orifice thus formed. At the same time the tension in the stem 53 is increasing. Under these changing conditions the valve is brought to rest and accelerated on its return motion, which is, in every respect, the reverse of the opening. As the valve nears its closed position the fuel pressure again builds up to its initial value. Just as the valve comes to rest the wave of pressure relief from 48 arrives and the action ceases. The proportions of the valve stem and head necessary

for this synchronism are best arrived at by experiment, although they may be calculated readily by assuming for the valve head simple harmonic motion for approximate results.

It will be obvious that this invention may be varied radically in design without departing from the spirit and scope of its application.

I claim as my invention:

1. In a fuel injection system, an hydraulic ram generator of injection pressure comprising a fuel filled duct, means for supplying fuel to this duct, a displacer having opposing abutments at opposite ends of said duct, engine-operated means for rapidly moving said displacer in a direction to increase the space available for fuel at one end of said duct while decreasing the space at the other or upstream end, an hydraulic accumulator adapted to receive at rising pressure the fuel so displaced at the upstream end of said duct, and a fixed abutment adapted to bear against the upstream abutment of said displacer at the end of its travel. 15

2. In a fuel injection system, a fuel-filled duct, means for supplying fuel to said duct, a displacer having opposing abutments at the opposite ends of said duct and stepped in diameter to provide an additional abutment in opposition to that at the upstream end of said duct, a similarly stepped cylinder into which said displacer is fitted, an hydraulic accumulator at the upstream end of 20 said duct, a fixed abutment adapted to limit the stroke of said displacer, and means for rapidly operating said displacer comprising a second hydraulic pressure accumulator, means for displacing liquid into said accumulator, an engine-operated valve adapted to release the pressure so produced, and a duct connecting said valve with the above-mentioned additional abutment of said displacer. 25

3. In a fuel injection system, an engine-operated hydraulic ram having as one of its elements a fuel-filled duct, an outwardly-opening long-stem automatic poppet injection valve, a duct connecting said first-named duct at its downstream end with said injection valve, the dynamic period of 30 said injection valve as determined by the mass of its head and the elasticity of its stem being equal to the time required for sound to travel twice the length of said first-named duct. 35

ROBERT E. NELSON.
